UNITED STATES PATENT OFFICE.

HENRY THURSTON, OF KINGSTON, ONTARIO, CANADA.

BOILER WATER-CIRCULATING DEVICE.

1,146,213.

Specification of Letters Patent. Patented July 13, 1915.

Application filed March 15, 1915. Serial No. 14,396.

To all whom it may concern:

Be it known that I, HENRY THURSTON, of 92 Barrack street, in the city of Kingston, Province of Ontario, Dominion of Canada, 5 have invented certain new and useful Improvements in Boiler Water-Circulating Devices, of which the following is a specification.

This invention relates to feed water devices adapted to be utilized in boilers and the like and the objects of the invention are to produce a positive circulation of the water in the boiler, to facilitate in removing scum and other foreign matter suspended in 10 the water, to simplify and reduce the number of working parts and other objects which will be shown hereafter, and it consists essentially of the improved construction of 15 water circulating device particularly described and set forth in the following specification and accompanying drawings forming part of the same.

In the drawings, Figure 1 is a transverse section of a marine boiler showing the improved water circulating device attached thereto. Fig. 2 is a longitudinal section of the same. Fig. 3 is a longitudinal section of part of the improved water circulating device showing the cylinder broken in the 20 center. Fig. 4 is a view partly sectional of the water feed pipe and check valve associated therewith.

Like characters of reference refer to like parts in the several drawings.

Referring to the drawings, A represents a boiler and B the water circulating device attached thereto. This boiler may be of any usual construction, that shown being of the Scotch or marine type which is well known 35 in the art and not forming part of the present invention, except in so far that the water circulating device is in combination therewith, it is deemed unnecessary to further enlarge upon the same.

The water circulating device B consists 45 of the horizontally disposed cylinder 1 which is provided at one end with a cover 2 formed integral therewith, such cover having a flanged outlet pipe 3 extending at 50 right angles therefrom and located on the lower side and adjacent to the outer periphery thereof, the other end of the said cylinder being provided with a cover 4 formed integral therewith having an orifice 5 through the center thereof and being pro-

vided with a plurality of orifices located near its outer periphery with which the bolts 6 are adapted to engage. This cylinder is further provided intermediate of its ends with an outlet orifice 7 extending through 60 the top of its outer periphery, the object of which will be made clear hereafter.

The flanged outlet pipe 3 is connected at one end to the pipe 8, the other end of which is in turn connected to the side plate of the 65 boiler A and adapted to communicate with the scum cock 9 mounted on the outer face of the said side plate.

10 represents a pipe provided at one end with a flange 11 having a plurality of 70 orifices therethrough adapted to engage with the bolts 6 whereby the said pipe is secured to the cylinder 1 in which position the bore of the pipe registers with the orifice 5 in the cover 4, the opposite end of the pipe 10 75 being provided with a stuffing box 12 having a thread around the inner periphery thereof with which the stuffing gland 13 is designed to make threaded engagement. This pipe is further provided on the lower 80 side of its outer periphery with a downwardly disposed branch pipe connection 14 located adjacent to the stuffing box 12.

15 represents a pipe which is adapted to 85 slidably fit the packing gland 13 and the stuffing box 12, the outer end of such pipe being provided with a flange 16 having a plurality of orifices therethrough, the inner end of the said pipe being tapered and designed to extend into the pipe 8 to a distance just beyond the bore of the branch pipe connection 14, the pipe 15 being of a size such that there is an annular space between the outer periphery of the said pipe and the inner periphery of the pipe 10 95 which is clearly illustrated in Fig. 3.

17 represents a pipe which is connected at one end to the elbow 18 which in turn is provided on its opposite end with a flange 19 having a plurality of orifices therethrough 100 designed to register with the orifices in the flange 16 and be secured thereto by bolts or the like, the other end of the pipe 17 being connected to the end plate 20 of the boiler A and being adapted to communicate with the check valve 21 mounted on the outer face of the said end plate, which check valve is in turn connected to the feed pump of the 105 boiler.

22 represents a suction pipe which is con- 110

nected at its upper end by threaded engagement with the branch pipe connection 14, such pipe extending vertically downwardly between adjacent nests of tubes and furnaces 5 to the bottom of the boiler.

The horizontally disposed cylinder, pipe 10, pipe 15, elbow 18, pipe 17 and pipe 8 are designed to be located just below the normal water level of the boiler.

- 10 The operation of the device is as follows: The feed pump of the boiler is started and water is forced through the check valve 21, the pipe 17, the elbow 18 and the pipe 15 being delivered through the tapered end of 15 the last said pipe into the pipe 10. In this operation the water discharged from the pipe 15 exerts an entraining action on the water located in the bottom of the boiler which circulates upwardly through the pipe 20 22 and discharges from the upper end thereof into the pipe 10 from whence it is discharged into the cylinder 1 and leaves the same through the orifice 7 located in the top of the outer periphery of the said cylinder. 25 When the feed pump is stopped this circulation of water has been found by experiment to continue its circulation, the operation of the pump only tending to initially create such circulation.
- 30 It will be clear that the water which circulates upwardly through the pipe 22 will carry with it a considerable amount of foreign matter suspended therein and this matter when discharged into the cylinder 1 will 35 be delivered into the pipe 3 and thence into the pipe 8 from which it can be blown off by means of the scum cock 9.

Although in the embodiment illustrated only one such device is shown in connection 40 with the boiler, it will be quite clear that to facilitate in producing such a circulation that the circulating devices may be arranged in a series, all being fed from the same inlet feed pipe.

45 Any suitable material may be utilized in the manufacture of the several parts of the water circulating devices, steel and cast iron being preferably employed.

As many changes could be made in the 50 above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. The combination with a boiler of a 60 water circulating device located below the normal water level of the said boiler, comprising a cylinder having an outlet orifice located in the top thereof, a pipe connected at one end to the said cylinder, a stuffing

box in the said pipe, a gland adapted to 65 make threaded engagement therewith, a feed pipe adapted to slidably fit the said stuffing box and form with the inner periphery of the first said pipe, an annular space, a suction pipe designed to be attached to the 70 lower side of the first said pipe adjacent to the said stuffing box, such suction pipe extending downwardly to the bottom of the said boiler and means for removing the scum from the water, as and for the purpose 75 specified.

2. The combination with a boiler of a water circulating device located below the normal water level of the said boiler, consisting of a horizontally disposed cylinder 80 having an outlet orifice through the top thereof an outlet pipe extending from one end of the said cylinder, the other end being formed with a cover having an orifice through the center thereof, a pipe provided 85 with a flange adapted to be secured to the said cover, a stuffing box on said pipe, a gland adapted to make threaded engagement therewith, a branch pipe connection located on the lower side of the outer periphery of 90 the said pipe adjacent to the said stuffing box, a suction pipe designed to make threaded engagement with the said branch pipe connection, a feed pipe adapted to slidably fit the gland and the said stuffing box having 95 its inner end tapered and adapted to form with the inner periphery of the first said pipe an annular space and means for removing the scum from the water, as and for the purpose specified.

3. The combination with a boiler of a feed water device adapted to be located below the normal water level of the said boiler, consisting of a cylinder having an outlet extending through the top thereof, such cylinder being provided with a cover formed integral therewith, a discharge pipe extending from the said cover the end of the said cylinder being provided with a cover having an orifice through the center thereof, a pipe 105 designed to be attached to the second said cover, a stuffing box on said pipe, a gland adapted to make threaded engagement therewith, a branch pipe extending from the lower periphery of the said pipe and located 110 adjacent to the said stuffing box, a suction pipe designed to be attached to the said branch pipe, a feed pipe adapted to slidably fit the said gland and stuffing box the inner end of the said pipe being tapered and adapted to 115 form an annular space with the inner periphery of the first said pipe, a pipe designed to be secured at one end to the outlet pipe, and a scum cock communicating with the last said pipe as and for the purpose specified.

4. In combination in a boiler, a device of the class described located above the normal

water level of the boiler comprising a horizontal cylinder having an outlet through the top thereof, a diminutive discharge pipe extending from the bottom of one end of the 5 said cylinder beyond the boiler surface, an L-shaped pipe extending from the other end of said cylinder and communicating therewith, a nozzle projecting into said L through which the feed water is adapted to be fed, a branch pipe extending from said L to the 10 bottom of the boiler, and a cock on said discharge pipe on the exterior of the boiler.

In witness whereof I have hereunto set my hand in the presence of two witnesses.

HENRY THURSTON.
